[57] **CLAIM**

The ornamental design for a combined garment bag and twin club bags, as shown and described.

DESCRIPTION

FIG. 1 is a side elevational view of a combined garment bag and twin club bags showing my new design with a shoulder strap in carrying position;

FIG. 2 is a top plan view of the combination bag as shown in FIG. 1, but with the strap re-located for illustrating the handle;

FIG. 3 is a side elevational view of the other side of the combination bag shown in FIG. 1;

FIG. 4 is a bottom plan view of the combination bag shown in FIG. 1;

FIG. 5 is an end view of one end of the combination bag shown in FIG. 1, the other end being a mirror image thereof;

FIG. 6 is a side elevational view of one side of the garment bag portion of the combined garment bag and

twin club bags when the garment bag is separated from the combination shown in FIGS. 1-5, the garment bag being shown in the carrying position;

FIG. 7 is a side elevational view of the other side of the garment bag portion as shown in FIG. 6;

FIG. 8 is an end view of one end of the garment bag portion shown in FIGS. 6 and 7;

FIG. 9 is a top plan view of the garment bag portion shown in FIGS. 6 and 7 but with the shoulder strap re-located for illustrating the handle;

FIG. 10 is a bottom plan view of the garment bag portion shown in FIGS. 6 and 7;

FIG. 11 is a side elevational view of one side of the garment bag portion of the combined garment bag and twin club bags when same is separated from the combination shown in FIGS. 1-5, the garment bag being shown in a hang up position but with the shoulder strap being omitted;

FIG. 12 is a side elevational view of the other side of the garment bag portion shown in FIG. 11;

FIG. 13 is an end view of one end of the garment bag portion shown in FIGS. 11 and 12, the other end being a mirror image;

FIG. 14 is a top plan view of the garment bag portion shown in FIGS. 11 and 12;

FIG. 15 is a bottom plan view of the garment bag portion shown in FIGS. 11 and 12;

FIG. 16 is a side elevational view of one side of the two club bags of the combined garment bag and twin club bags when those two club bags are separated from the combination shown in FIGS. 1-5, and when those two club bags are joined together, the other side elevational view being a mirror image thereof;

FIG. 17 is an end view of one end of the two joined together club bags shown in FIG. 16, the other end being a mirror image thereof;

FIG. 18 is a top plan view of the two joined together club bags shown in FIG. 17;

FIG. 19 is a bottom plan view of the two joined together club bags shown in FIG. 17;

FIG. 20 is a side elevational view of one side of each of the two club bags when those bags are separated from the others and from the garment bag, the other side elevational view of the other side of each of those two club bags being shown in FIG. 16;

FIG. 21 is an end view of one end of one of the two club bags whose side elevation views are shown in FIGS. 16 and 20, the other end being a mirror image thereof;

FIG. 22 is a top plan view of that one of the two club bags shown in FIG. 21;

FIG. 23 is a bottom plan view of each of the two club

bags whose side elevation views are shown in FIGS. 16 and 20;

FIG. 24 is an end view of one end of the other of the two club bags whose side elevation views are shown in FIGS. 16 and 20, the other end being a mirror image thereof; and

FIG. 25 is a top plan view of that one of the two club bags shown in FIG. 24.
